AUTOMATIC BLAST TORCH

Samuel C. Brody, Brighton, Mass.

Application August 10, 1936, Serial No. 95,220

8 Claims. (Cl. 158—35)

This invention relates to automatic blast torches. While particularly adapted for use with a torch of the self-generating type which employs a combustion burner mounted in conjunction with the pressure generating unit, it may be used with a torch which does not employ such combustion burner but instead depends upon the flame from the priming unit being continuously played on the outer end of the pressure generating unit to cause the torch to continue to generate a blast flame.

The main object of my invention is to increase the general operating efficiency of the torch. Other objects are to simplify and make practically foolproof the construction of the torch and to reduce the manufacturing cost thereof.

In order that the many advantages of my invention may be more readily understood and appreciated, reference is made to the accompanying specification and drawing wherein I describe and illustrate an embodiment of my invention which I have found efficient, economical, and unusually satisfactory in service and well adapted to the requirements of commercial manufacture.

Fig. 1 is an enlarged elevation, partly in section, of an automatic blast torch of the self-generating type employing a combustion burner and equipped with a novel jet unit in accordance with my invention.

Fig. 2 shows my novel jet unit applied to an automatic blast torch of the type which does not employ such combustion burner, and

Figs. 3 and 4 are enlarged detail views of my novel jet unit.

In Fig. 1, I have illustrated a self-generating blast torch equipped with combustion burner. Such torch includes a generating unit 10 and a combustion burner 11 assembled therewith.

A priming or starting unit 12, such as shown in Fig. 2, may or may not be used with the torch of Fig. 1. If a starting or priming unit 12 is used, it may, if desired, be connected to the pressure generating unit 10 in any suitable manner, as by means of the clamping member 13 or its equivalent shown in Fig. 2.

The pressure generating unit comprises a fuel reservoir 14, a wick tube 15, a wick 16 in said tube and extending into said reservoir, and a jet unit 17 mounted within the outer end of the wick tube.

My present invention is particularly directed to such jet unit which in accordance with my concept embodies certain new constructional and

functional features never heretofore attained in the art.

In all prior art torches with which I am familiar, the design of the jet unit has been such as to afford no opportunity for expansion or volatilization of the gases produced by the generating unit prior to their delivery into the combustion burner.

As a consequence, such gases were discharged from the jet orifice of the jet unit forthwith into the combustion burner for immediate mixture with the air entering such burner. This tended to retard, delay or impair maximum or practically perfect combustion and hence greatly reduced the operating efficiency of the torch in general, especially the blast flame.

My novel jet unit not only overcomes these disadvantages but introduces certain new and important advantages which greatly increase the operating efficiency of the torch.

Among these are the following:—a hotter, more uniform, much stronger, and more constant blast flame at the discharge end of the burner, and hence a much faster and much greater generation and conduction of heat back to the wick and wick tube of the pressure generating unit, thereby resulting in the vaporization of a much greater volume of gas in a shorter time and a far greater volatilization of such vaporized gases than ever heretofore obtained.

Torches equipped with my invention are characterized by their ability to continuously deliver a blast flame of maximum heat and pressure at all times, which flame is uniform and constant and does not intermittently diminish or increase in intensity or volume, due to changes in temperature of the burner and/or torch, changes in operating position, and/or other causes which heretofore made impossible completely satisfactory continuous operation of the torch.

My novel jet unit consists of a member formed at one end for quick detachable connection with the outer end of the wick tube and at its other end for quick detachable connection with the inner end of the combustion burner. Preferably, although not necessarily, the jet unit is externally threaded as at 18 and 19 at or adjacent to its end portions. The threaded portions 18 and 19 engage with corresponding internal threads 20 and 21 formed, respectively, on the wick tube and combustion burner.

Intermediate of the threaded portions 18 and 19, the jet unit is formed to provide a sealing collar or shoulder 22. One face of this collar is

adapted to abut the outer end of the wick tube and tightly seal these parts against gas-pressure or other leakage. The other face of said collar is adapted to be abutted by the inner end of the combustion burner to tightly seal these parts against gas-pressure or other leakage.

The threads 18 are relatively fine and the threads 19 are relatively coarse. The fine thread enables the jet unit to be tightly screwed and sealed into the wick tube, and the coarse thread enables the combustion burner to be screwed on and off the jet unit easily by hand. Thus the burner may be easily unscrewed from the jet unit without unscrewing the jet unit from the wick tube.

The screw threaded end portions 18 and 19 of the jet unit are hollow and separated by the wall of the collar 22 which extends therebetween. This wall provides with said hollow screw-threaded portions separate chambers 23 and 24 respectively which communicate with each other through the small jet orifice 25 in said wall.

The chamber 23 is a gas forming and heating chamber and also acts as a gas reservoir. The chamber 24 is a gas heating, volatilizing and expansion chamber.

In operation, after the torch has been primed, lighted, and has started to self-generate gas the accentuated heat from the burner is rapidly carried back through the jet unit to the wick and wick tube until a maximum heat has developed in the wick tube jet unit and burner, thereby causing the maximum fuel vaporization and gas formation in the wick tube, and at the same time heating the gas chamber 23 to a point where the stored and discharging gases therein are highly volatilized. These gases discharge through orifice 25 into chamber 24 where they have an opportunity to expand and pre-mix with the pre-heated air entering said chamber through the burner tube, thus further increasing the volatilization of the said mixture, so that when said mixture enters the burner tube it is in highly combustible condition and when ignited will take on only such necessary additional air through the burner tube as will give it the maximum and ideal combustion qualities.

This maximum and ideal combustion insures a continuous, uniform and steady blast flame, as well as continuous and uniform delivery of heat back to the pressure generating and gas forming units.

Charring of the wick and resultant clogging of the jet orifice is practically eliminated in my construction, due to the fact that the end portion 18 of the jet unit is spaced away from the wick in the wick tube as well as the burner which is spaced away from the wick tube itself.

As previously suggested, my novel jet unit is equally advantageous when used with a torch which does not employ a combustion burner, as shown in Fig. 2, and has practically the same advantages and merits as it has when used in conjunction with a combustion burner, except that it does not emit as hot or voluminous blast flame as when used with a combustion burner. In the torch of Fig. 2, the flame from the priming unit is continuously played on the outer end of the pressure generating unit within which my novel jet unit is mounted.

If desired, the jet unit may be so constructed as to eliminate the threaded portion 18, and when so modified is assembled with the wick tube in any practical manner.

Various other modifications in construction

and arrangement may obviously be resorted to within the spirit and scope of my invention, as defined by the appended claims.

What I therefore claim and desire to secure by Letters Patent is:—

1. A jet unit adapted to be interposed between the pressure generating unit and the combustion burner of a self-generating blast torch, comprising a member having a portion projecting into the inner end of the combustion burner so as to be heated thereby and providing an expansion chamber in communication with the pressure generating unit and open to the interior of the burner within which chamber the gases emitted from said pressure generating unit enter and expand into contact with the heated inner wall surface of said chamber to absorb the heat therefrom and thereby enter the combustion burner in expanded and highly volatilized form.

2. The jet unit of claim 1, said unit also having a perimetrically extending portion in rear of said chamber-forming projection for abutment against the inner end of the burner to seal the parts against leakage.

3. A jet unit adapted to be interposed between the pressure generating unit and the combustion burner of a self-generating blast torch, comprising a member having a portion sub-dividing the same into separate but communicating chambers disposed within and open to the interior of the pressure generating unit and combustion burner, respectively, the chamber which is disposed within the combustion burner being a heated expansion chamber within which the gases emitted from said pressure generating unit enter and expand into contact with the heated inner wall surface of said chamber to absorb heat therefrom and thereby enter the combustion burner in expanded and highly volatilized form.

4. The jet unit of claim 3, the portion which subdivides the same extending perimetrically of the unit and presenting faces adapted respectively for abutment by the inner end of the burner and the outer end of the pressure generating unit to seal said parts against leakage.

5. The jet unit of claim 3, the portion which sub-divides the same having a jet orifice interiorly thereof by means of which the chambers communicate with each other.

6. A jet unit adapted to be interposed between the pressure generating unit and the combustion burner of a self-generating blast torch, comprising a member having hollow axially extending chamber-forming portions projecting respectively into the interior of the pressure generating unit and burner and having an intermediate portion separating said chamber-forming portions, the chamber which is disposed within the combustion burner being a heated expansion chamber within which the gases emitted from said pressure generating unit enter and expand into contact with the heated inner wall surface of said chamber to absorb heat therefrom and thereby enter the combustion burner in expanded and highly volatilized form.

7. In an automatic blast torch, a pressure generating unit, and a combustion burner, and a jet unit connecting the pressure generating unit and the combustion burner, said jet unit comprising a member having a chamber-forming portion projecting beyond the outer end of the pressure generating unit and into the adjacent end of the combustion burner and providing an outwardly open chamber, said jet unit having a

wall portion forming the inner end of said chamber and provided with a jet orifice in communication with the pressure generating unit, and said wall portion extending perimetricaly of said 5 jet unit and providing a sealing face for abutment by the outer end of said pressure generating unit to seal the parts against leakage, the chamber which is disposed within the combustion burner being a heated expansion chamber 10 within which the gases emitted from said pressure generating unit enter and expand into contact with the heated inner wall surface of said chamber to absorb heat therefrom and thereby enter the combustion burner in expanded and 15 highly volatilized form.

8. In a blast torch, a pressure generating unit, a combustion burner, and a single jet unit detachably connecting said parts, and having two separate chambers, one chamber extending into the pressure generating unit, and the other chamber extending into the combustion burner, there being an orifice connecting said chambers, and the last named chamber being a heated expansion chamber within which the gases emitted from said pressure generating unit enter and 10 expand into contact with the heated inner wall surface of said chamber to absorb the heat therefrom and thereby enter the combustion burner in expanded and highly volatilized form. 5
